UNITED STATES PATENT OFFICE.

MARGARET R. FITCH, OF PALERMO, CALIFORNIA, ASSIGNOR TO CECILIA B. TUTTLE, OF BERKELEY, CALIFORNIA.

DESIGN FOR ROMPERS.

46,988.

Specification for Design.

Patented Feb. 23, 1915.

Application filed October 7, 1914. Serial No. 865,601. Term of patent 7 years.

To all whom it may concern:

Be it known that I, MARGARET R. FITCH, a citizen of the United States, residing in Palermo, county of Butte, and State of California, have invented a new, original, and ornamental Design for Rompers, of which the following is a specification, reference being had to the accompanying drawings, forming part thereof.

I claim:

The ornamental design for rompers, as shown.

MARGARET R. FITCH.

Witnesses:

W. W. HEALEY,
M. E. EWING.
